US0D1022878S

(12) **United States Design Patent** (10) **Patent No.:** **US D1,022,878 S**
(45) **Date of Patent:** **** Apr. 16, 2024**

(54) **BATTERY PACK**

(71) Applicant: **Dragonfly Energy Corp.**, Reno, NV
(US)

(72) Inventor: **Bayartsetseg Hopkins**, Reno, NV (US)

(73) Assignee: **Dragonfly Energy Corp.**, Reno, NV
(US)

(**) Term: **15 Years**

(21) Appl. No.: **29/880,278**

(22) Filed: **Jul. 20, 2023**

Related U.S. Application Data

(62) Division of application No. 29/858,079, filed on Oct. 27, 2022, now Pat. No. Des. 997,092, which is a division of application No. 29/744,598, filed on Jul. 30, 2020, now Pat. No. Des. 971,827.

(57) **CLAIM**

The ornamental design for a battery pack, as shown and described.

DESCRIPTION

FIG. 1 is a top, front, right side perspective view of a battery pack, according to my new design;

FIG. 2 is a left side elevation view thereof;

FIG. 3 is a right side elevation view thereof;

FIG. 4 is a top plan view thereof;

FIG. 5 is a bottom plan view thereof;

FIG. 6 is a front elevation view thereof; and,

FIG. 7 is a rear elevation view thereof.

The dot-dash broken lines represent boundaries of the claimed design and form no part of the claimed design. The dash-dash broken lines depict portions of the battery pack that form no part of the claimed design.

1 Claim, 3 Drawing Sheets
